Thurston & Water.

UNITED STATES PATENT OFFICE.

WILLIAM E. SELL, OF CANTON, OHIO, ASSIGNOR TO THE GILLIAMS MANUFACTURING COMPANY, OF SAME PLACE.

BIT.

SPECIFICATION forming part of Letters Patent No. 634,769, dated October 10, 1899.

Application filed June 20, 1899. Serial No. 721,229. (No model.)

To all whom it may concern:

Be it known that I, WILLIAM E. SELL, a citizen of the United States, residing at Canton, in the county of Stark and State of Ohio, have 5 invented a certain new and useful Improvement in Bits, of which the following is a full, clear, and exact description, reference being had to the accompanying drawings.

The object of my invention is to provide a 10 comparatively cheap bit which will not injure a horse's mouth.

To this end the invention consists in the construction and combination of parts hereinafter described, and pointed out definitely 15 in the claim.

In the drawings, Figure 1 is a plan view of a bit embodying my invention, the bit-body being made of one piece. Fig. 2 is a similar view, partly in section, of a bit embodying 20 my invention wherein the bit-body is made of two pieces connected together in the usual way. Fig. 3 is a plan view, partly in section, of a rubber protector; and Fig. 4 is a view of the same, looking in the direction of the arrow in Fig. 3.

Referring to the parts by letters, A represents a bit-bar which may be made of one piece, as in Fig. 1, or two pieces fastened together by interlocking eyes *a*, as shown in Fig. 30 2, both constructions being well known in this art.

B represents rings which are mounted in eyes *a'* on the outer ends of the bit-bar and serve as means for attaching the reins.

C represents a rubber protector, which consists of a tubular body *c* and plano-convex disks *c'*, which are integral with the body and normally lie substantially at right angles thereto. These protectors are preferably 40 made of what is known as "sponge-rubber." The outer face of each disk is plane, while the inner side is convex, and the disk is substantially circular in form. The tubular body projects at right angles from the convex side of the disk and from a point at or very close to the marginal edge thereof. The tubular body part and the disk near its edge are split, whereby the body may be spread open, so as to permit of the insertion of the

bit-bar. When the bit-bar has been inserted 50 in the body part *c* of the protector, the bar is embraced by said body part, and the disks lie just inside of the rein-rings and substantially at right angles to the bit-bar. The rubber disks *c'* are covered on both sides by leather 55 pieces *D D'*, the marginal edges of which are sewed together. The inner piece has a hole near its margin, through which the bit-bar passes. The body part *c* is also covered by a leather envelop, the outer ends of which are 60 made fast to the inner leather cover *D'* of the disks.

When the bit-bar is made of one piece, the body part of the protector is made, approximately, as long as the bit-bar, and the disks 65 are formed on the opposite ends thereof. When, however, the bit-bar is made of two pieces, the body part of the protecting-piece is made of two pieces, and each has a disk on its outer end. The leather envelop for the 70 body of the protecting-piece extends only slightly beyond the inner ends of the body pieces of the rubber protector, so that it does not interfere with the relative movement of the two parts of the bit-bar.

Having described my invention, what I claim as new, and desire to secure by Letters Patent, is—

The combination of a bit-bar having eyes at its outer ends and rein-rings in said eyes, 80 with a protector *C* made of sponge-rubber and consisting of plano-convex disks, and a tubular body which is integral with the disks and projects substantially at right angles to the disks from the convex sides thereof and from 85 points close to their marginal edges, a leather covering for said body, and leather coverings for said disks consisting each of two pieces of leather stitched together at their marginal edges, the inner pieces being also stitched to 90 the adjacent ends of the leather covering of the body, substantially as specified.

In testimony whereof I hereunto affix my signature in the presence of two witnesses.

WILLIAM E. SELL.
